UNITED STATES PATENT OFFICE.

EDWIN H. BELL, OF CHICAGO, ILLINOIS, ASSIGNOR TO THE RAILROAD SUPPLY COMPANY, OF CHICAGO, ILLINOIS, A CORPORATION OF ILLINOIS.

TIE-PLATE.

No. 873,707.

Specification of Letters Patent.

Patented Dec. 17, 1907.

Application filed November 13, 1906. Serial No. 343,220.

To all whom it may concern:

Be it known that I, EDWIN H. BELL, a citizen of the United States, residing at Chicago, county of Cook, State of Illinois, have invented a certain new and useful Improvement 5 in Tie-Plates, and declare the following to be a full, clear, and exact description of the same, such as will enable others skilled in the art to which it pertains to make and use 10 the same, reference being had to the accompanying drawings, which form a part of this specification.

My invention relates in general to railroad track fastenings, and more particularly to 15 tie plates.

It is customary to interpose metallic plates between railroad rails and the supporting ties in order to prevent the wearing away of the ties by the rails, and in order to 20 more firmly secure the rails to the ties and thereby prevent both longitudinal creeping and lateral spreading of the rails with respect to the ties.

It is desirable that tie plates should have 25 ribs or flanges on their under surfaces to prevent movement of the plates upon the ties, and should also have shoulders on their upper surfaces to prevent spreading of the rails. In order that tie plates may be as light as 30 possible, and at the same time possess the requisite strength they may be advantageously provided with longitudinal grooves in their upper surfaces.

The primary object of my invention is to 35 provide a tie plate which, when applied to a tie will not creep thereon, which will prevent spreading of the rails, and which will possess the requisite structural strength with a minimum weight.

40 A further object of my invention is to provide an improved process for economically and expeditiously making tie plates.

A still further object of my invention is to 45 provide a tie plate which will be simple in construction, inexpensive in manufacture and efficient in use.

My invention will be more fully described hereinafter with reference to the accompanying drawing in which the same is illustrated 50 as embodied in two convenient and practical forms, and in which

Figure 1 is a perspective view of the rolled blank; Fig. 2 a perspective view of a tie plate formed by shearing the blank shown in Fig. 55 1; and Fig. 3 a perspective view of a modi-

fied form of tie plate made from the blank shown in Fig. 1.

Similar reference characters are used to designate similar parts in the several figures of the drawings.

The metal of which the tie plate is to be formed is passed between suitable rolls so as to form a blank such as shown in Fig. 1 comprising parallel flanges B', B' extending longitudinally beneath the surface of the plate, 65 intermediate flanges b', b' of less depth than the flanges B', parallel grooves D', and d' arranged above the flanges B', and b', and flanges C', and C² projecting upwardly from the side edges of the blank.

70 Portions of the flanges C' and C² are sheared from the blank along planes at right angles to the surface of the plate thereby forming shoulders to be engaged by the edge of the base of a rail to prevent the spreading 75 of the rails of a track.

The flanges may be sheared intermediate of their ends as shown in Fig. 2 so as to leave a pair of shoulders c', c' adjacent one end of the plate and a second pair of shoulders c², 80 c² adjacent the opposite end of the plate. The distance between the pairs of shoulders corresponds to the width of the rail base so that the rail will be prevented from lateral movement relative to the plate through the 85 engagement of the edges of the base of the rail with the pairs of shoulders.

In Fig. 3 I have shown a modified form of tie plate made from the blank shown in Fig. 1 by shearing off the flanges C' and C² so as to 90 leave only one pair of shoulders c³ and c⁴ adjacent one end of the plate. If desired the shoulders in each pair may be of unequal lengths in order that the plates when used on curves may be placed longitudinally upon 95 the ties and at the same time afford supports for the edge of the rail base which extends in an inclined direction across the ties. I have indicated in Fig. 3 the shoulders c³ and c⁴ of unequal lengths, the shoulder c⁴ being shorter 100 than the shoulder c³.

Each plate is provided with holes through which spikes may be driven to tightly secure the same to a tie. A single spike hole E' is provided through the end of the plate extending inside of the rail base while two spike holes are punched through the plate at points adjacent the outer edge of the rail base.

110 A tie plate embodying my invention may

be securely fastened to a tie by driving the depending flanges B' and b' into the grain of the wood, and will positively prevent the spreading of the rail owing to the pair of shoulders on the upper surface thereof against which the edge of the rail base engages. By forming the parallel grooves in the upper surface of the plate it is rendered lighter in weight and thereby rendered cheaper and more economical in construction.

It will be observed that the shoulder also serves to prevent the base of the rail cutting the head of the spike inasmuch as the hole for the spike is formed in line with the shoulder.

The compression of the fibers of the tie when the plate is seated owing to the arched construction of the flanges of the plate, makes a stronger seat for the plate and also prevents the decay of the tie.

From the foregoing description it will be observed that I have invented an improved tie plate and have also invented an improved process by means of which tie plates may be economically and expeditiously made.

Having now fully described my invention what I claim as new and desire to secure by Letters Patent is:

30 1. A tie plate comprising a flat body portion having a pair of longitudinal ribs projecting from one face near the side edges thereof and shallower intermediate ribs arranged parallel with the said pair of ribs and 5 side flanges of less thickness than the body

portion projecting laterally and then upwardly from the body portion to form shoulders adapted to engage with the base flange of a rail.

2. A tie plate having a series of longitudinal grooves formed in its upper face and having side portions of less thickness than the body portion, said side portions extending laterally and then upwardly so as to form shoulders to engage the base flange of a rail, 40 a series of longitudinal ribs arranged on the under side of the plate directly beneath the longitudinal grooves, the intermediate ribs being of less depth than the outside ribs and the outside ribs being arranged at the intersection of the side portions with the main body portion.

3. The process of manufacturing tie plates which consists in first rolling the metal to form a blank having parallel ribs on its under-surface, parallel grooves in its upper surface arranged in alinement with said ribs, and thin flanges projecting outwardly and upwardly along the side edges thereof, and subsequently shearing off portions of said 55 flanges at planes at right angles to the surface of the blank to form shoulders projecting upwardly from the side edges of the plate.

In testimony whereof, I sign this specification in the presence of two witnesses.

EDWIN H. BELL.
